UNITED STATES PATENT OFFICE.

JOSEPH FOURESTIER SIMPSON, OF VINELAND, NEW JERSEY, ASSIGNOR OF ONE-HALF TO
WILLIAM NICE, JR., OF PHILADELPHIA, PENNSYLVANIA.

GAME APPARATUS.

No. 905,941.

Specification of Letters Patent.

Patented Dec. 8, 1908.

Application filed November 12, 1907. Serial No. 401,786.

To all whom it may concern:

Be it known that I, JOSEPH FOURESTIER SIMPSON, a citizen of the United States, and a resident of Vineland, Cumberland county, 5 New Jersey, have invented a certain new and useful Improvement in Game Apparatus, of which the following is a specification

My invention relates to improvements in game apparatus, and the object of my invention is to furnish a game, to be played with a ball or projectile, in which both skill and chance will play a part and which will give to the player a considerable amount of exercise.

My invention consists of a board or alley, 15 which may be varied greatly in length to suit different conditions or requirements, along which the ball or projectile is rolled or slid. The board or alley is arranged to cause the ball or projectile in its passage to be projected into the air. This may be done in a number of ways, but I prefer to accomplish it by means of an obstruction, which will give to a ball or projectile passing it a range. To the rear of the board or alley is a target, 25 preferably furnished with a number of spaces or holes into one of which the ball or projectile falls, each of the holes or spaces represents a value and the game is counted by adding the value of the successive shots of 30 each player. In order that there may be no disputes as to the value of the several shots the apparatus may be furnished with a counting device to be actuated by the ball as it passes through or out of the holes in the target. This counting device may simply indicate the value of each shot or it may be arranged to indicate the value of the sum of several shots.

In the accompanying drawings forming 40 part of this specification, and in which similar letters of reference indicate similar parts throughout the several views:—Figure 1, is a side elevation of my game apparatus. Fig. 2, a plan of Fig. 1; Fig. 3, a perspective view; Fig. 4, a vertical sectional view through one 45 form of target showing counting device and means for operating it; Fig. 5, a perspective view of counting device and means for actuating it; Fig. 6, a front view of target of circular plan. Fig. 7, a section of Fig. 6 on line 7—7; Fig. 8, a plan of one of the levers to which the projectile passes after leaving the target.

The board *a* along which the balls are 50 rolled is furnished with an upraised part or

obstruction *b* which causes the ball upon coming in contact with it to be projected into the air. At some distance to the rear of obstruction *b* is placed a target *c* which is furnished with a number of holes or perforations *d* into one of which it is the object of the player to place the ball. The several holes or perforations have each their own value and the player scoring the highest value in one or more shots wins. 60

After passing through the target the ball falls to the floor, which preferably slopes from this point downward towards the player, and is returned to him through a gutter *e* on one side of the board *a*. A similar gutter *f* is provided upon the opposite side of the table *a* to return a ball that might roll off this side of the table before reaching the obstruction *b*. 65

At the end of the table *a* the floor is sloped 70 in a triangular manner, as shown best at *g*, Figs. 1 and 3, upward from the entrance to gutter *e* toward and past the gutter *f*, the purpose of this construction being to prevent the formation of a pocket at the end of table 80 *a* and to direct all balls that may fall between the end of the board *a* and the target, or through the target, to the gutter *e*. 75

h are screens of wire, canvas or some suitable material placed at the rear end of the 85 sides of the apparatus to keep the balls from falling or rolling away.

The holes in the target *c* should be furnished with some form of counting device. In Figs. 6 and 7 I have shown tags *i* which are 90 suitably numbered and swingingly supported from their upper ends. An object passing into one of the holes will strike and displace the tag *i* and thus call attention to the particular hole that the object has entered. 95

In Figs. 4 and 5 a form of automatic registering counting device is shown. In this case the ball or projectile after passing through the hole *d* engages a pivoted lever *j* and resting upon the outer end of this lever, of which there is one for each hole *d*, depresses it. A cord, chain or rod *k* is connected to the lever and to a lever *l* which is loosely carried by a shaft *m*. *n* is a pawl carried by lever *l* which engages a ratchet *o* which is kept from a reverse movement by a pawl *p*. The ratchet *o* is fast upon the shaft *m*. When the ball passes through the hole *d* and engages the lever *j* the free end of this lever falls drawing down the cord, chain or rod *k* and the lever *l* 105 110

and the pawl *n* moves the ratchet *o* one, two or more spaces as the drop of the lever *j* may dictate. A counterweighted arm *r* returns the levers *j*—*l* to their original positions as soon as the ball is dropped from the lever *j*.

Fast upon and turning with the shaft *m* is a drum *s* to the periphery of which are hinged, parallel to shaft *m*, numbered cards *t*. There should be as many teeth upon the 10 ratchet wheel *o* as there are cards upon the drum *s* and every movement of said ratchet will be followed by a corresponding movement of said drum. If the ratchet be moved one tooth the drum will be moved so that one 15 card will be moved away from the window *u* and the next card will take its place. If the ratchet be moved two or three spaces, the second or third card will appear opposite the window.

20 For purposes of simplicity we will suppose that the free ends of all of the levers *j* connected with the upper tier of holes *d* in the target can fall an equal distance which will, through the connections *k* fastened to 25 these levers and to the lever *l*, cause a rocking of the lever *l* sufficient to cause the pawl *n* to move the ratchet *o* the space of one tooth. This will cause the drum *s* to be moved sufficiently to move the card at the window *u* 30 away and bring the next card on the drum opposite the window; hence every time that a ball passes into one of the openings *d* in the upper tier of openings and passes to and depresses the lever *j* one card will be moved 35 away from the window *u* and the next card will be moved to this window.

If the free ends of the levers *j* in the second tier of holes *d* are all adapted to be moved by a ball a distance double that of the levers 40 in the upper tier of holes the connections *k* between them and the lever *i* will move the latter twice as far as did the connections from the levers of the first tier of holes, hence 45 a ball passing into any of the second tier of holes will cause the pawl *n* to move the ratchet *o* the space of two teeth and the drum *s* will be rotated so as to bring every other one of the cards *i* opposite the window.

50 If the levers *j* connected with the lower tier of holes *d* be adapted to be moved by

the ball three times the distance of the levers connected with the upper tier of holes they will actuate the lever *l* so that the pawl *n* moves the ratchet *o* the space of three teeth and every third one of the cards is brought 55 to the window for each complete movement of the levers in the lower tier of holes.

The cards *t* are numbered consecutively and the arrangement counts the value of the shots. For instance if the cards be numbered in multiples of 100 five consecutive shots in any of the holes in the upper tier of holes would bring the 500 card opposite the window *u* or one shot in the second tier of holes 60 and one shot in the lower tier of holes 65 would count the same and the mechanism would be operated to bring the 500 card to the window.

The arrangement of the drum *s* and the cards *t* is well known and as I make no claim 70 upon them they will not need further description.

I do not desire to limit myself to any particular form of counting or indicating device, any of the well known forms of apparatus 75 for this purpose may be used.

Having thus described my invention, I claim:

1. In a game apparatus, in combination, a board along which a projectile is adapted to travel, an apertured target at the rear of and above said board, and an obstruction upon said board, in front of and spaced from said target, adapted to cause said ball to leave said board and continue its flight towards 80 said target in the air.

2. In a game apparatus, in combination, a board along which a projectile is adapted to be rolled, an obstruction for trajecting said projectile, an elevated apertured target at 90 the rear of and spaced from said obstruction, pivoted levers arranged in said apertures adapted to be engaged and operated by the projectile after passing through said apertures, and an indicating device adapted to 95 be operated by the movement of said levers.

JOSEPH FOURESTIER SIMPSON.
